UNITED STATES PATENT OFFICE.

ALPHA B. CULP, OF WAKARUSA, INDIANA.

BARN STRUCTURE.

SPECIFICATION forming part of Letters Patent No. 792,970, dated June 20, 1905.

Application filed December 1, 1904. Serial No. 235,077.

To all whom it may concern:

Be it known that I, ALPHA B. CULP, a citizen of the United States, residing at Wakarusa, in the county of Elkhart and State of 5. Indiana, have invented new and useful Improvements in Barn Structures, of which the following is a specification.

My invention pertains to improvements in barn structures.

10 It has principally for its object to effect the firm bracing together of the individual members of the framing, especially of the roof-rafters, as also of the studding and their connecting members or pieces, whereby unobstructed room - space may be secured and cheapness of construction, lightness, and great strength are obtainable.

15 The nature of said invention consists of certain structural features, substantially as hereinafter more fully disclosed, and particularly pointed out by the claims.

20 In the accompanying drawings, illustrating the preferred embodiment of my invention, Figure 1 is a perspective view thereof. Fig. 25 2 is an enlarged detailed gable-end view of the structure with parts broken away. Fig. 3 is a cross-section produced through said end. Fig. 4 is a detail bottom view of one of the gable ends of the structure. Fig. 5 is a broken-30 away end view.

25 In the carrying out of my invention I suitably construct the framing 1 of the barn structure generally as shown, the "comb" or ridge of the roof being preferably composed of short pieces of scantling 2, utilized for that purpose and suitably clamped edgewise between the rafters 3 by the binding action of braces later described. Between one end of each short piece 2 and the sides of the oppo-40 site meeting end portions of two rafters is suitably secured a triangular piece 4 by nail- ing or otherwise for holding said rafter meeting end portions together or in contact. At each end or gable of the roof the rafters 3 are 45 arranged relatively quite close together, and between each two of these closely-arranged rafters are suitably nailed or otherwise secured the reduced upper end portions of end stud members 5, reaching downward past and 50 secured to the upper end cross or horizontal

pieces or joists 6 of the framing and further secured to and lapping the lower corresponding stud members 5^a, the thus lapping of one stud member upon the other having a strengthening effect.

55

Stretching from and converging toward the extreme inner upper surface of each end or gable of the roof and extending along diagonal lines in the direction of the length of the latter are duplicate series of what may be termed "pull-braces" 7 7^a, consisting of suitable lengths of scantling. Each of said series of braces has its lateral pieces or members 7^a extending toward and preferably bearing or abutting laterally at their divergent ends 60 against the upper longitudinal or horizontal framing-joists 8 at a point upon each of the latter about equidistant of its ends and mid-length. The central or intermediary members 7 of each series extend toward and preferably bear in like manner against said longitudinal or horizontal framing-joists 8 about at their mid-lengths, the divergent ends of opposed or corresponding members abutting one against the other. The divergent ends of the 70 members of each of the series of said braces are secured to opposite or contiguous rafters 3, preferably by clips or yokes 9 9^a, embracing and preferably let into said rafters, with their arms passed through said members and 75 fitted with nuts screwed thereon up against the latter. Likewise the convergent ends of the lateral members 7^a of each series of said braces are secured to the inner rafters of each end, two thereof preferably, by clips or yokes 80 85 10, similarly embracing and let into said rafters, with their arms passed through said members and equipped with nuts screwed up against the latter. The intermediary members 7 of each brace series have also their convergent ends 90 in like manner secured to said inner rafters, preferably by clips or yokes 11, embracing and let into the latter, with their arms passed through said members and equipped with nuts. Said members, however, have applied 95 to their inner or underneath surfaces at said ends an angular plate 12 common to both members and through which the arms of the clips or yokes 11 pass and up against which are screwed the nuts of the latter, said members 100

thus being rigidly connected together as well as secured to said rafters. Also applied to the framing 1 upon the inside and over the door-openings are suitably secured additional 5 braces 13 to further brace or strengthen the structure, more especially at these points, as desired.

From the foregoing it will be noted that a light yet strong and rigidly-braced structure 10 is provided, while it is devoid of any beams or joists spanning its interior from side to side, thus furnishing room - space therein wholly free of such obstructing joists or beams from the ground or floor surface clear to the 15 roof, the desirability of which in this class of structures is apparent. Also it is noted that a structure erected upon the aforesaid lines, although it should be overturned by the force of the wind, would withstand destruction and 20 even stand being rolled over and over without collapsing, besides having no parts which would be thrown out of place in the event of such a mishap.

Latitude is allowed as to details herein, as 25 they may be changed as circumstances suggest without departing from the spirit of my invention.

I claim—

1. A structure of the character described, 30 having its roof-rafters equipped with two sets of braces secured thereto along diagonal lines, the upper ends of one set being secured to the extreme upper portions of the gable ends and the lower ends thereof secured to the framing 35 at about the mid-length of the latter, the other set of braces having their upper ends secured also to the extreme upper portions of said gable ends and having their lower ends secured to said framing at a point intermediate 40 of the mid-length and the ends of said framing.

2. A structure of the character described, having its roof-rafters equipped with two sets of braces secured thereto along diagonal lines,

the upper ends of one set being secured to the extreme upper portions of the gable ends and 45 the lower ends thereof secured to the framing at about the mid-length of the latter, the other set of braces having their upper ends secured also to the extreme upper portions of said gable ends and having their lower ends secured 50 to said framing at points intermediate the mid-length and ends of said frame, and clips or yokes effecting the securing of said braces in position to said rafters.

3. A structure of the character described, 55 having its gable-end rafters arranged at short intervals apart and secured together, stud members having their upper ends interposed therebetween, and additional stud members, the aforesaid stud members lapping upon the 60 latter stud members.

4. A structure of the character described, having its roof-rafters equipped with two sets of braces secured thereto along diagonal lines, 65 the upper ends of one set being secured to the extreme upper portions of the gable ends and the lower ends thereof secured to the framing at about the mid-length of the length of the latter, the other set of braces having their upper ends secured, also the extreme upper portions 70 of said gable ends, and having their lower ends secured to said framing at a point intermediate of the mid-length and the ends of said framing, yokes or clips embracing certain of said rafters and having their arms passed through said braces, and an angle-plate applied to certain of said braces, at their gable-end portions, with the arms of certain of said clips or yokes passed through and secured to 75 said plate.

In testimony whereof I affix my signature in presence of two subscribing witnesses.

ALPHA B. CULP.
